UNITED STATES PATENT OFFICE.

LOUIS A. HAWTHORNE, OF NEWARK, NEW JERSEY, ASSIGNOR TO STEEL UTILITIES,
INCORPORATED, A CORPORATION OF NEW YORK.

METAL-WORKING MACHINE.

1,241,251.

Specification of Letters Patent. Patented Sept. 25, 1917.

Application filed March 13, 1914. Serial No. 824,385.

To all whom it may concern:

Be it known that I, LOUIS A. HAWTHORNE, a citizen of the United States, residing at Newark, New Jersey, have made certain Improvements in Metal-Working Machines, of which the following is a specification.

The invention relates to machines for perforating structural shapes and the like for fabrication and more especially to distance determining devices for properly feeding and locating the work with reference to perforating mechanisms.

Objects of the invention will be set forth hereinafter in part, and in part will be obvious herefrom, said objects being effected and realized by the instrumentalities and combinations set forth in the appended claims.

The invention consists in the novel parts, constructions, arrangements, combinations and improvements herein shown and described.

The accompanying drawings, referred to herein, and constituting a part hereof, illustrate one embodiment of the invention, and serve with the description to explain the principles of the invention.

Of the drawings,

Figure 1 is a plan, with parts in section and with parts broken away, of a machine embodying the invention;

Fig. 2 is a fragmentary plan, on an enlarged scale with parts in section and with parts broken away, of the distance determining device shown in the lower central part of Fig. 1;

Fig. 3 is an elevation looking at Fig. 2 from the foot;

Fig. 4 is a fragmentary perspective view of the distance determining rings or disks shown in plan in Fig. 2;

Fig. 5 is a fragmentary plan, with parts broken away, of the rings or disks shown at the lower right hand part of Fig. 2; and

Fig. 6 is a sectional view on the line A—B of Fig. 5.

Referring to the accompanying drawings, illustrating by way of example, one embodiment of the invention, suitable means are provided for forwarding a structural shape, such as an I-beam α , relatively to the punching devices, and in cooperation and conjunction with the forwarding means, settable in means whereby the shape is stopped in proper position to be perforated at the de-

sired point or points by the tool-equipped means.

I have chosen to show a particular form of work forwarding means such as is set forth in application for patent, Serial No. 60 790,085, of Theodore P. Payne, filed Sept. 16, 1913. Briefly described, said means comprises devices acting upon the shape to urge or progress it forward by frictional contact, such as rollers 1, carried by suitable supports, and preferably arranged in a horizontal series, the punching mechanisms being located at an intermediate point along the pathway of the shape over said rollers. Said rollers 1 are suitably driven, and as 70 embodied, the shafts 2 thereof are supported by journals 3, and have bevel gears 4, which gears 4 intermesh with corresponding gears 5 upon shafts 6. Said shafts 6 are journaled in suitable supports 7, there being a shaft 75 6 for the rollers on one side of the punching mechanism and another shaft 6 for the rollers on the other side of the punching mechanism. Said shafts 6 are driven in a suitable manner as by a motor 8 connected 80 thereto by suitable gearing 9.

With the embodied form of my distance determining device, I have employed devices or mechanisms coöperating with the rollers 1, which devices or mechanisms permit travel of the shape α under impulsion of rollers 1 and act also under control of the distance determining device to stop the shape in accordance with the setting of the distance determining device. As embodied, 90 I have utilized the particular form of mechanism shown and described in the hereinbefore mentioned application Ser. No. 790,085, of Theodore P. Payne. Said mechanism comprises a head 10 with which head the 95 forward end of the shape α is in contact as the shape is impelled forward by the rollers 1. To said head 10 is fixed a geared rack 11, extending backwardly alongside the shape α , said rack being supported in a proper manner by rollers and guides (not shown herein).

The distance determining device is connected directly to the rack 11, by means of a pinion 12 upon a shaft 13 of the distance determining device, said pinion meshing with the gear-teeth on the rack 11, the shaft 13 of the distance determining device thus moving exactly proportionally with the rack 11 and the shape α .

As embodied, the shaft 13 is journaled in bearings 14 and 15 in the ends of a relatively long, hollow, horizontal casing 16, and said bearings are preferably provided with bushings 17. The casing 16 has a longitudinal opening throughout its length, preferably about a quadrant in width, through which extend and travel the connections between the mechanism internal to the casing and the mechanism external thereto. Said casing 16 has an internal thread 18 extending throughout the length thereof. The shaft 13 within the casing 16 is squared or otherwise equivalently formed, as shown at 19. Mounted on the squared portion 19 of shaft 13, is a nut 20, said nut having an external thread meshing with the internal thread 18 of the casing 16. The nut 20 is mounted upon the squared portion 19 of shaft 13, thereby turning with shaft 13, and the casing 16 being stationary, the nut 20 is traveled longitudinally along the squared portion 19 of shaft 13 as said shaft rotates. Fixed to or integral with the nut 20 is a sleeve 21 extending along and inclosing the shaft 13, said sleeve 21 being squared internally to fit the part 19, and being exteriorly of cylindrical form.

At its other end the sleeve 21 is provided with an abutment for the purpose of keeping in position certain other parts, later to be described, which are mounted upon said sleeve 21, said abutment being shown herein as an internally threaded ring 22 screwed on to a corresponding thread on the ends of the sleeve 21.

Sleeved or journaled on the sleeve 21 is a cylinder 23, which is rotatable relatively to the sleeve 21 at the proper time in the sequence of operation of the device. The nut 23 at its left hand end in Fig. 2 is provided with crown teeth 23^a, which are adapted to engage with the teeth 20^a, as hereinafter described. Fixed to or integral with said cylindrical member 23 is an extension, formed as a sleeve 24 extending along and inclosing the sleeve 21, but being rotatable thereon with the cylindrical member 23. Said sleeve or extension 24 is provided on its exterior surface with a thread 25. The cylinder 23 is utilized in obtaining the ultimate or smaller distance settings, and has coöperating therewith certain distance keys, which will be described later.

Encircling the threaded sleeve 24 and having an internal thread in mesh with the thread 25 of the sleeve 24 is a nut 30. Fixed to or integral with the nut 30 is a neck 31 extending out through the aperture in casing 16. To neck 31 is fixed a longitudinal rack 32, said rack being provided with suitable guide ways, such as 33, along which it travels, the mechanism within the casing 16 traveling proportionately therewith.

In accordance with certain features of the

invention, there are provided rotary members traveling in definite relation to the work and having coöperating therewith settable devices representing distance denominations or values settable to control the movement and position of said rotary members, and thereby to position and stop the shape relatively to the tool-equipped means.

As embodied, said rotary devices connect directly to the rack 33 controlling its longitudinal movement, and thus controlling the rotation of the shaft 13 and thus controlling the longitudinal travel and stopping of the head 10 and the shape α . As embodied, said means comprise a series of disks rotatable relatively to each other, and nested one within another. A supporting casing 34 extends out horizontally from and is carried by the casing 16. Said casing 34 is provided with a wall 35, extending about and inclosing the nested, rotatable disks. Supported in the casing 34 is a fixed, upwardly extending shaft 36, which serves as an axis for the rotatable disks, said shaft 36 at its upper end being supported by a bracket 37, fixed to the wall 35. Concentric upon and rotatable relatively to said shaft 36 is a plate or disk 38, which plate 38 is provided with an upwardly extending flange or face 39 extending out from the disk 38. Upon the outer face or surface of the flange 39 is a gear 40 in mesh with the gear-teeth upon the rack 32, the wall 35 of the casing 34 being recessed to permit the engagement of the gears. In the upper face (as arranged in the figure of the drawings) of the disk 34 is formed an arcuate groove or slot 45. Superposed on said disk 38 is a disk 46 likewise rotatable about the shaft 36. Upon said disk 46 is supported a group or series 105 of keys 50, slidably in apertures in disk 46, and adapted to coöperate with the slot 45 in the disk 38.

As embodied, said key-board device comprises an arcuate plate 47 carried upon a segmental circular support 48 fixed to the disk 46 in a suitable manner, as by nuts 49. In the plate 47 are a series of apertures spaced apart at definite distances and of suitable length, into which apertures the keys 50 are projected when they are set or depressed. The lower ends of the keys 50 are in the form of pins 51 projectable into and retractable out of the slots 45. Between the heads of the keys 50 and the plate 47, are coiled springs 52 for the purpose of retracting the keys. Beneath the plate 47 is an oscillating ring 55, in which ring 55 are apertures through which the pins 51 of the keys 50 project. On the pins 51 are conoidal portions 56, said conoidal portions when the key is retracted have their small ends just within the respective apertures in the ring 55. The large ends or heads of the conoidal enlargements in this position are pressed 130

- against the plate 47 by the spring 52, thus serving as a stop for the retracted keys. The apertures in the ring 55 are just of a size to permit the conoidal enlargements 56 to pass therethrough. The ring 55 is held by suitable spring and stop mechanism (not shown) in a position whereby the pins 51 of the keys 50 are at one side of the corresponding apertures in ring 55.
- When a key 50 is depressed, its conoidal portion 56, in passing through its aperture rotates the ring 55 slightly against its spring, and after the conoidal portion 56 has passed through the aperture in the ring 55, the ring is moved back by its spring, with the top of the conoidal portion 56 beneath the ring 55 thus locking the set key in position. Upon setting a succeeding key, the ring 55 will be again similarly moved, and as its conoidal enlargement passes through the aperture in the ring 55, the preceding set key is released, and the new key being set is in its turn locked beneath the ring 55.
- Rotatably mounted above the plate or disk 46 is a plate or disk 60. The disk 46 has an upwardly extending sleeve 61, which sleeve embraces the shaft 36, the disk 60 being centrally apertured to fit about and rotate about the sleeve 61. Carried upon said disk 60 is a group or series of keys 62, reciprocable in apertures in disk 60, and generally similar in construction to the keys 50 already described. Said keys 62 are carried in apertures in a supporting plate 63, which plate is mounted upon an arcuate segmental support 64, which support is mounted upon the disk 60. Said keys 62 are provided with conoidal portions 65 passing through and coöperating with apertures in a locking ring 66, which ring may be generally similar to the ring 55 already described. Suitable retracting springs 67 coöperate with the keys 62 in the same manner as the springs 52 coöperate with the keys 50. In the disk 46 are a plurality of slots 68, located and proportioned to correspond to distance values, with which slots the keys 62, carried by the disk 60, coöperate, the keys 62 projecting into the slots 68 when set or depressed, and clearing the slots when released or retracted.
- Mounted above the disk 60 is a concentric circular disk 71 fixed to shaft 36. Said disk 71 carries a key supporting plate 72, having a series of keys 73 reciprocably mounted in apertures in disk 71 and in plate 72, and similar in construction and operation to the series or groups of keys previously described. Said key carrying plate 72 is mounted upon a circular arcuate support 74 fixed upon the plate 71. The group or series of keys 73 have a locking ring 76, which ring is similar in construction and operation to the locking rings 66 and 55 already described. The keys 73 coöperate with a series of arcuate slots 77 formed in the disk 60, said keys when set projecting into the slots, and when retracted being free therefrom.
- Means are also provided for giving the ultimate or more minute feed and feed control than that given by the rotatable disks just described. In the embodied form such additional means give the feed or distance determinations for fractions of an inch. In said means there is fixed to the rack 32 an arcuate support 80 (shown in elevation in Fig. 3 and in section in Fig. 2) which extends upwardly from the rack 32 in front of the opening in and along cylinder 16, and about and in contiguity with the cylindrical member 23. The support 80 carries a similar plate 80^a spaced away therefrom, said plates being provided with apertures in said supporting plates, which keys coöperate with grooves or slots in the exterior of the cylindrical member 23. Assuming that the device is constructed to operate in feet and inches, the disk 38, and the keys 50 may be regarded as determining or controlling the tens of feet; the disk 46 and keys 62 as determining feet or units of feet; the disk 60 and keys 73 as determining or controlling inches, and the keys carried by the plate 80 and coöperating with the cylinder 23 as determining or controlling fractions of an inch, and as embodied controlling the feed by sixteenths of an inch.
- As embodied four rows of keys are utilized, said rows being arranged vertically or in helical circumferential lines as to Fig. 3, and designated respectively by reference numerals 81, 82, 83 and 84. Said keys are provided with retracting springs 85 in compression between the key heads and the surface of the arcuate plate 80. Said plate 80 is spaced away from a plate 86 likewise carried by the rack 32 and having apertures therein in which the lower ends of the keys are slidable to pass into and out of engagement with the slot in the surface of the cylinder 23. Between the plates 80 and 86 are located a slideable locking plate 87, which operates similarly to the locking rings 55 already described. Said plate 87 is slidably mounted upon suitable supports, and is urged in one direction by spring 88. The keys are provided with conoidal enlargements 89 operating in conjunction with the slideable plate 87 to lock a set key in position similarly to the coöperation and coaction of keys 50 with ring 55 already described. Said conoidal enlargements 89 also serve as stops against the interior of the plate 80 for the retracted keys.
- The grooves in the cylindrical member 23 are formed in the surface thereof of helicoidal form and of the same pitch as the internal thread 18 of casing 16 and also of the same pitch as the thread on the nut 20

and the thread 25 on the sleeve 24. Said slots extend in the embodied form only partially about the member 23, there being one slot corresponding to each of the series of keys 81, 82, 83 and 84, said slots being indicated respectively by reference numerals 90, 91, 92 and 93.

On the face or left hand end of cylindrical member 23 (referring to Fig. 3) are formed a series of crown teeth, having slanting peripheral faces of substantially the same pitch as the screw threads 18, 20 and 25, and having short faces disposed substantially parallel to the axis of the cylinder 23.

10 15 A corresponding set of like teeth are formed in the adjacent face of the nut 20, but oppositely disposed so that they will lock together at the proper time in the operation of the device. A suitable spring 94 serves 20 to hold the nut 20 and cylinder 23 apart so that the teeth just escape each other until relative movement of the two are required in the distance determining operation.

25 The manner of operation of the hereinbefore described mechanisms is substantially as follows:

30 A shape α is in position upon the rollers 1, which rollers are driven, through the connections described, from the motor 8 (Fig. 1). Said rollers may of course be driven either continuously or intermittently as best suited to the work being done and the organization of a particular machine. The shape α upon the rotating rollers 1 contacts with the head 10, and presses thereagainst. The rack 11, carrying the head 10, being geared to the shaft 13 by the pinion 12, the head 10 and therewith the shape α can move forwardly only as permitted by 35 40 the successive setting of the distance determining device.

45 It may be assumed that the next distance setting to be made involves a measurement including tens of feet, feet, inches and sixteenths of an inch. Correspondingly one of the pins 50, one of the pins 62, one of the pins 73, and one of the pins carried by the plate 80 will be set or pushed inwardly and locked in that position by the corresponding 50 locking plates already described.

This will permit the head 10 and rack 11 to travel forward a distance corresponding to the setting made, and the head and rack may start into motion in various ways, as 55 by the throwing in of a hand switch, or of an automatically operated switch, operated by the completion of the setting or otherwise for the motors 8 and 100, in both forward driving of the work and return of the 60 mechanism for new work. So far as concerns many features of the invention, one or more of the distance pins may be a locking pin, and the setting of another pin may be sufficient to start the device into operation.

As the head 10 and rack 11 travel forward, shaft 13 is rotated, and the nut 20 rotates with the shaft 13 by reason of its being mounted upon the squared portion 19. As nut 20 also meshes with the stationary 70 thread 18 upon the interior of the casing 16, the nut travels forward (that is to the right in Figs. 2 and 3), proportionately to the travel of the work α . With the nut 20, the entire structure over to the collar 22 travels 75 along to the right, including the rack 32.

The rack 32 through gear teeth 40 rotates disk 38. The disk 38 rotates with the rack 32 until the set pin or key of the series 50 reaches the end of the slot 45. Thereupon, 80 the disk 46 begins rotating, being drawn along by the pin 50 in the end of the slot 45. When by reason of such travel of the disk 46, the set key 62 reaches the end of the corresponding slot 68, the disk 60 is caused 85 to rotate, being drawn around by said pin 62 as it rests in the end of the slot 68. This rotation continues until the entire series of disks is brought to rest by the set pin or key 73 reaching the end of the corresponding slot 77, as will be fully understood from the foregoing.

At this juncture, by reason of the disks 38, 46 and 60 being brought to rest, and the shaft 13 continuing to rotate, the spring 94 95 is compressed, and the nut 20 and the cylinder 23 approach each other. The teeth 20^a and 23^a thus pass into alignment and their faces then engage due to the rotation. It will be understood that by reason of the 100 shape and location of the grooves 90, 91, 92 and 93, in the cylindrical member 23, and the coöperating keys the further movement of cylinder 23 will be rotational as well as translational, and will measure from 105 the last integral inch setting, which was recorded or determined by the set pin 73. The nut 20 and cylindrical member 23 being in a definite and predetermined position, the further rotation and forward or translational movement of the nut 20, after teeth 20^a and 23^a have passed into engaging position, will be determined by the amount of rotation permitted to cylinder 23 by the set pin of one of the series 81, 82, 83 and 84 and 115 its coöperating groove in the member 23. The thread 25 on the sleeve 24 will permit the requisite forward movement of the nut 20 and member 23 to the right with respect to the now stationary nut 30 and rack 32. 120 The cylindrical member 23 being brought to rest by the corresponding set key, reaching the end of its groove the shaft 13 is stopped, bringing the rack 11 and the head 10 to rest at precisely the position and after the distance of travel for which the distance determining device was set.

Suitable restoring devices are provided, and a spring 95 serves to restore the cylinder 23 to position. Likewise a coiled spring 130

96, coiled about the sleeve 61, and having one end fixed to the stationary plate 71 and the other end fixed to said sleeve 61, restores the plates to position for a new setting of 5 feet and inches.

Suitable means for returning the head 10 to position for receiving a new piece of work *x* are provided, and as embodied a motor 100 is connected by a suitable gearing 101 to shaft 13. Said motor may be called 10 into action by suitable automatically operated or hand operated devices.

From all the foregoing it will be understood that a machine has been provided embodying and realizing the objects and advantages herein set forth, together with other objects and advantages. It will be further understood that changes may be made from the particular construction herein 20 shown and described, within the scope of the accompanying claims, without departing from the principles of the invention, and without sacrificing its chief advantages.

What I claim as my invention, and desire 25 to secure by Letters Patent is:

1. A machine for punching structural shapes including in combination punching means, and means for successively progressing and stopping a shape in proper position 30 to be punched, said means including a head against which the end of the shape abuts as it travels, a rack bar extending along the shape and traveling therewith, and a distance determining device comprising a pinion meshing with said rack, a shaft upon 35 which said pinion is fixed, an externally threaded nut rotating with and traveling along said shaft, an internally threaded cylinder inclosing said nut and with which 40 the thread on said nut engages, a rack bar connected to travel with said nut, and a plurality of concentric rotatable disks, one of said disks having a gear meshing with said last mentioned rack bar, various disks having 45 slots therein, and having also keys adapted to be set to engage in slots on an adjacent disk to determine the amount of travel of one disk with respect to another.

2. A machine for punching structural 50 shapes including in combination punching means, and means for successively progressing and stopping a shape in proper position to be punched, said means including a head against which the end of the shape abuts as 55 it travels, a rack bar extending along the shape and traveling therewith, and a distance determining device comprising a pinion meshing with said rack, a shaft upon which said pinion is fixed, an externally 60 threaded nut rotating with and traveling along said shaft, an internally threaded cylinder inclosing said nut and with which the thread on said nut engages, a rack bar connected to travel with said nut, and a plurality of concentric rotatable disks, said 65

disks representing distance denominations and having arcuate slots representing respectively values in said distance denomination, and a series of keys carried by said respective disks the keys representing distance values and being projectable into the slots on an adjacent disk to determine the amount of travel of one disk with respect to another, one of said disks having a gear meshing with said rack. 70 75

3. A machine for punching structural shapes including in combination punching means, and means for successively progressing and stopping a shape in proper position to be punched, said means including a head against which the end of the shape abuts as it travels, a rack bar extending along the shape and traveling therewith, and a distance determining device comprising a pinion meshing with said rack, a shaft upon 80 which said pinion is fixed, an externally threaded nut rotating with and traveling along said shaft, an internally threaded cylinder inclosing said nut and with which the thread on said nut engages, a rack bar 85 connected to travel with said nut, and a plurality of concentric rotatable disks, one of said disks having a gear meshing with said last mentioned rack bar, various disks having slots therein, and having also keys 90 adapted to be set to engage in slots on an adjacent disk to determine the amount of travel of one disk with respect to another, said disks having an initial position and means for automatically restoring them to 95 such position. 100

4. A machine for punching structural shapes including in combination punching means and means for successively progressing and stopping a shape in proper position to be punched, said means including a head against which the end of the shape abuts as it travels, a rack bar extending along the shape and traveling therewith, and a distance determining device comprising a pinion meshing with said rack, a shaft upon which said pinion is fixed, an externally threaded nut rotating with and traveling along said shaft, an internally 105 threaded cylinder inclosing said nut and with which the thread on said nut engages, a rack bar connected to travel with said nut, and a plurality of concentric rotatable disks, one of said disks having a gear meshing with said last mentioned rack bar, various 110 disks having slots therein, and having also keys adapted to be set to engage in slots on an adjacent disk to determine the amount of travel of one disk with respect to another, said disks having an initial position and 115 spring means for automatically restoring them to such position. 120

5. A machine for punching structural shapes including in combination punching means, and means for successively progressing 125

one of said disks having a gear meshing with said rack and a restoring spring against which said disks are rotated.

against which the end of the shape abuts as it travels, a rack bar extending along the shape and traveling therewith, and a distance determining device comprising a pinion meshing with said rack, a shaft upon which said pinion is fixed, an externally threaded nut rotating with and traveling along said shaft, an internally threaded cylinder inclosing said nut and with which the thread on said nut engages, a rack bar connected to travel with said nut, and a plurality of concentric rotatable disks, one of said disks having a gear meshing with said last mentioned rack bar, various disks having slots therein, and having also keys adapted to be set to engage in slots on an adjacent disk to determine the amount of travel of one disk with respect to another and auxiliary means for permitting further motion of said shaft and nut after said disks are stopped by the engagement of said keys and slots, and means for automatically restoring said auxiliary means to initial position.

13. A machine for punching structural shapes including in combination punching means, and means for successively progressing and stopping a shape in proper position to be punched, said means including a head against which the end of the shape abuts as it travels, a rack bar extending along the shape and traveling therewith, and a distance determining device comprising a pinion meshing with said rack, a shaft upon which said pinion is fixed, an externally threaded nut rotating with and traveling along said shaft, an internally threaded cylinder inclosing said nut and with which the thread on said nut engages, a plurality of concentric rotatable disks, said disks having slots therein and keys settable to engage the slots in another of the said disks to determine the amount of travel of one disk with respect to another, and connections between said disks and said nut whereby the travel and stopping of the shape is controlled from said disks, an initial stop for said disks and automatic means for restoring said disks to initial position. 11

14. A machine for punching structural shapes including in combination punching means, and means for successively progressing and stopping a shape in proper position to be punched, said means including a head against which the end of the shape abuts as it travels, a rack bar extending along the shape and traveling therewith, and a distance determining device comprising a pinion meshing with said rack, a shaft upon which said pinion is fixed, an externally threaded nut rotating with and traveling along said shaft, an internally threaded cylinder inclosing said nut and with which the thread on said nut engages, a plurality of concentric rotatable disks, said disks 115
120
125
130

11. A machine for punching structural shapes including in combination punching means, and means for successively progressing and stopping a shape in proper position to be punched, said means including a head against which the ends of the shape abuts as it travels, a rack bar extending along the shape and traveling therewith, and a distance determining device comprising a pinion meshing with said rack, a shaft upon which said pinion is fixed, an externally threaded nut rotating with and traveling along said shaft, an internally threaded cylinder inclosing said nut and with which the thread on said nut engages, a rack bar connected to travel with said nut, and a plurality of concentric rotatable disks, one of said disks having a gear meshing with said last mentioned rack bar, various disks having slots therein, and having also keys adapted to be set to engage in slots on an adjacent disk to determine the amount of travel of one disk with respect to another and auxiliary means for permitting further motion of said shaft and nut after said disks are stopped by the engagement of said keys and slots, said auxiliary means comprising a series of keys settable to permit and determine such further movement of said nut and shaft.

60 and smart. 12. A machine for punching structural shapes including in combination punching means, and means for successively progressing and stopping a shape in proper position
65 to be punched, said means including a head

- representing distance denominations, said disks having slots therein representing distance values, and series of keys mounted on said disks, the series representing a distance 5 denomination and the various keys in a series representing distance values, said keys being respectively settable to engage in a slot in an adjacent disk to determine the amount of travel of one disk with respect to another, and connections between 10 said disks and said nut whereby the travel and stopping of the shape is controlled from said disks.
15. A machine for punching structural shapes including in combination punching means, and means for successively progressing and stopping a shape in proper position to be punched, said means including a head against which the end of the shape abuts as 15 it travels, a rack bar extending along the shape and traveling therewith, and a distance determining device comprising a pinion meshing with said rack, a shaft upon which said pinion is fixed, an externally threaded nut rotating with and traveling along said shaft, an internally threaded cylinder inclosing said nut and with which the thread on said nut engages, a plurality of concentric rotatable disks, said disks representing distance denominations, and means carried by said respective disks for engaging another disk and connections between said nut and said disks to control the travel and stopping of the shape relatively to said 35 punching means.
16. A machine for punching structural shapes including in combination punching means, and means for successively progressing and stopping a shape in proper position to be punched, said means including a head against which the end of the shape abuts as it travels, a rack bar extending along the shape and traveling therewith, and a distance determining device comprising a pinion meshing with said rack, a shaft upon which said pinion is fixed, an externally threaded nut rotating with and traveling along said shaft, an internally threaded cylinder inclosing said nut and with which the thread on said nut engages, a plurality of concentric rotatable disks, said disks representing distance denominations and means carried by said respective disks for engaging another disk and connections between 45 said nut and said disks to control the travel and stopping of the shape relatively to said punching means, and means operating automatically to restore said disks for a new setting.
- 40 17. A machine for punching structural shapes including in combination punching means, and means for successively progressing and stopping a shape in proper position to be punched, said means including a head against which the end of the shape abuts as it travels, a rack bar extending along the shape, and traveling therewith, a distance determining device comprising a pinion meshing with said rack, a shaft upon which said pinion is fixed, an externally threaded nut rotating with and traveling along said shaft, an internally threaded cylinder inclosing said nut and with which the thread on said nut engages, a plurality of concentric rotatable disks, said disks representing distance denominations, and means for permitting and preventing rotation of one disk relatively to another to control the travel 110 and stopping of the shape relatively to said punching means.
- 45 18. A machine for punching structural shapes including in combination punching means, and means for successively progressing and stopping a shape in proper position to be punched, said means including a head against which the end of the shape abuts as it travels, a rack bar extending along the shape, and traveling therewith, and a distance determining device comprising a pinion meshing with said rack, a shaft upon which said pinion is fixed, an externally threaded nut rotating with and traveling along said shaft, an internally threaded cylinder inclosing said nut and with which the thread on said nut engages, a plurality of concentric rotatable disks, said disks representing distance denominations, and means for permitting or preventing rotation of one of said disks relatively to another and connections between said nut and said disk to control the travel of the shape relatively to the punching means.
- 50 19. A machine for punching structural shapes including in combination punching means, and means for successively progressing and stopping a shape in proper position to be punched, said means including a head against which the end of the shape abuts as it travels, a rack bar extending along the shape, and traveling therewith, a distance determining device comprising a pinion meshing with said rack, a shaft upon which said pinion is fixed, an externally threaded nut rotating with and traveling along said shaft, an internally threaded cylinder inclosing said nut and with which the thread on said nut engages, a plurality of concentric rotatable disks, said disks representing distance denominations, and means for permitting and preventing rotation of one disk relatively to another to control the travel 115 and stopping of the shape relatively to said punching means.
- 55 20. A machine for punching structural shapes including in combination punching means, and means for successively progressing and stopping a shape in proper position to be punched, said means including a head against which the end of the shape abuts as it travels, a rack bar extending along the shape, and traveling therewith, and a distance determining device comprising a pinion meshing with said rack, a shaft upon which said pinion is fixed, an externally threaded nut rotating with and traveling along said shaft, an internally threaded cylinder inclosing said nut and with which the thread on said nut engages, a plurality of concentric rotatable disks, said disks representing distance denominations, and means for permitting or preventing rotation of one of said disks relatively to another and connections between said nut and said disk to control the travel of the shape relatively to the punching means.

- ing and stopping a shape in proper position to be punched, said means including a head against which the end of the shape abuts as it travels, a rack bar extending 5 along the shape, and traveling therewith, a distance determining device comprising a pinion meshing with said rack, a shaft upon which said pinion is fixed, an externally threaded nut rotating with and traveling 10 along said shaft, an internally threaded cylinder inclosing said nut and with which the thread on said nut engages, a plurality of concentric rotatable disks, said disks representing distance denominations, and selectively settable means for permitting and 15 preventing rotation of one disk relatively to another to control the travel and stopping of the shape relatively to said punching means.
- 20 21. A machine for punching structural shapes including in combination punching means, and means for successively progressing and stopping a shape in proper position to be punched, said means including a head against which the end of the shape abuts as it travels, a rack bar extending 25 along the shape and traveling therewith, a distance determining device comprising a pinion meshing with said rack, a shaft upon 30 which said pinion is fixed, an externally threaded nut rotating with and traveling along said shaft, an internally threaded cylinder inclosing said nut and with which the thread on said nut engages, a plurality of concentric rotatable disks, said disks 35 representing distance denominations, and means for permitting or preventing rotation of one of said disks relatively to another and lineally traveling connections between said nut and said disk to control the travel of the shape relatively to the punching means.
- 25 24. A machine for punching structural shapes including in combination punching means, and means for successively progressing and stopping a shape in proper position to be punched, said means including a head against which the end of the shape abuts as it travels, a rack bar extending 40 along the shape and fast to said head, a pinion engaging said rack bar, a shaft on which said pinion is fixed, a member rotating with said shaft and traveling proportionately therewith, a rack bar fixed to travel longitudinally with said member, a plurality of disks representing distance 45 values and geared to said rack, and means carried by one disk for engaging another of said disks to control the travel and stopping of said shape relatively to said punching means.
- 30 25. A machine for punching structural shapes including in combination punching means, and means for successively progressing and stopping a shape in proper position to be punched, said means including a head against which the end of the shape abuts as it travels, a rack bar extending 55 along the shape and fast to said head, a pinion engaging said rack bar, a shaft on which said pinion is fixed, a member rotating with said shaft and traveling proportionately therewith, a rack bar fixed to travel longitudinally with said member, a plurality of disks representing distance 60 values and geared to said rack, and selectively settable means representing distance values carried by one disk for engaging another of said disks to control the travel and stopping of said shape relatively to said punching means.
- 35 26. A machine for punching structural shapes including in combination punching means, and means for successively progressing and stopping a shape in proper 65 to said punching means.

- a plurality of disks representing distance values, and geared to said rack and means for permitting and preventing rotation of one disk relatively to another to control the travel and stopping of said shape relatively to the punching means.
27. A machine for punching structural shapes including in combination punching means, and means for successively progressing and stopping a shape in proper position to be punched, said means including a head against which the end of the shape abuts as it travels, a rack bar extending along the shape and fast to said head, a pinion engaging said rack bar, a shaft on which said pinion is fixed, a member rotating with said shaft and traveling proportionately therealong, a rack bar fixed to travel longitudinally with said member, a plurality of disks representing distance values and geared to said rack, and means representing different distance values for permitting and preventing rotation of one disk relatively to another to control the travel and stopping of said shape relatively to the punching means.
28. A machine for punching structural shapes including in combination punching means, and means for successively progressing and stopping a shape in proper position to be punched, said means including a head against which the end of the shape abuts as it travels, a rack bar extending along the shape and fast to said head, a pinion engaging said rack bar, a shaft on which said pinion is fixed, a member rotating with said shaft and traveling proportionately therealong, a rack bar fixed to travel longitudinally with said member, a plurality of disks representing distance values and geared to said rack, and selectively settable means carried by one disk for engaging another of said disks to control the travel and stopping of said shape relatively to said punching means, and automatic means for restoring said disks.
29. A machine for punching structural shapes including in combination punching means, and means for successively progressing and stopping a shape in proper position to be punched, said means including a head against which the end of the shape abuts as it travels, a rack bar extending along the shape and fast to said head, a pinion engaging said rack bar, a shaft on which said pinion is fixed, a member rotat-

ing with said shaft, and traveling proportionately therealong, a rack bar fixed to travel longitudinally with said member, a plurality of disks representing distance values and geared to said rack, and selectively settable means carried by one disk for engaging another of said disks to control the travel and stopping of said shape relatively to said punching means, and means for restoring said disks preparatory to a new setting.

30. A machine for punching structural shapes including in combination punching means, and means for successively progressing and stopping a shape in proper position to be punched, said means including a head against which the end of the shape abuts as it travels, a rack bar extending along the shape and fast to said head, a pinion engaging with said rack bar, a shaft on which said pinion is fixed, a member rotating with said shaft and traveling proportionately therealong, a rack bar fixed to travel longitudinally with said member, a plurality of disks representing distance values, connections between said rotating member and disks to cause said disks to travel proportionately to said rotating member, and means for permitting and preventing rotation of one disk relatively to another to control the travel and stopping of said shape relatively to the punching means.

31. A machine for punching structural shapes including in combination punching means, and means for successively progressing and stopping a shape in proper position to be punched, said means including a head against which the end of the shape abuts as it travels, a rack bar extending along the shape and fast to said head, a pinion engaging said rack bar, a shaft on which said pinion is fixed, a member rotating with said shaft and traveling proportionately therealong, a plurality of disks representing distance values, connections between said rotating member and disks to cause said disks to travel proportionately to said rotating member, and selectively settable means for permitting and preventing rotation of one disk relatively to another to control the travel and stopping of said shape relatively to the punching means.

32. A machine for punching structural shapes including in combination punching means, and means for successively progressing and stopping a shape in proper position to be punched, said means including a head against which the end of the shape abuts as it travels, a rack bar extending along the shape and fast to said head, a pinion engaging said rack bar, a shaft on which said pinion is fixed, a member rotating with said shaft and traveling proportionately therealong, a plurality of disks representing distance values, connections between said rotating member and disks to cause said disks

to travel proportionately to said rotating member, and selectively settable means for permitting and preventing rotation of one disk relatively to another to control the travel and stopping of said shape relatively to the punching means, and means for restoring said disks preparatory to a new setting.

33. A machine for punching structural shapes including in combination punching means, and means for successively progressing and stopping a shape in proper position to be punched, said means including a head against which the end of the shape abuts as it travels, a rack bar extending along the shape and fast to said head, a pinion engaging said rack bar, a shaft on which said pinion is fixed, a member rotating with said shaft and traveling proportionately therewith, a plurality of disks representing distance values, connections between said rotating member and disks to cause said disks to travel proportionately to said rotating member, and means representing distance values for permitting and preventing rotation of one disk relatively to another to control the travel and stopping of said shape relatively to the punching means.

34. A machine for punching structural shapes including in combination punching means, and means for successively progressing and stopping a shape in proper position to be punched, said means including a head against which the end of the shape abuts as it travels, a rack bar extending along the shape and fast to said head, a pinion engaging said rack bar, a shaft on which said pinion is fixed, a member rotating with said shaft and traveling proportionately therewith, a plurality of disks representing distance values, connections between said rotating member and disks to cause said disks to travel proportionately to said rotating member, and selectively settable means representing distance denominations and values for permitting and preventing rotation of one disk relatively to another to control the travel and stopping of said shape relatively to the punching means.

35. A machine for punching structural shapes including in combination punching means, and means for successively progressing and stopping a shape in proper position to be punched, said means including a shaft rotatable proportionately to the travel of said shape, and a plurality of rotatable disks representing distance denominations, connected to move with said shaft, and means for permitting and preventing rotation of said disks to control the travel and stopping of said shape relatively to the punching means.

36. A machine for punching structural shapes including in combination punching means, and means for successively progressing and stopping a shape in proper position

to be punched, said means including a shaft rotatable proportionately to the travel of said shape, and a plurality of rotatable disks representing distance denominations connected to move with said shaft, and selectively settable means for permitting and preventing rotation of said disks to control the travel and stopping of said shape relatively to the punching means.

37. A machine for punching structural shapes including in combination punching means, and means for successively progressing and stopping a shape in proper position to be punched, said means including a shaft rotatable proportionately to the travel of said shape, and a plurality of rotatable disks representing distance denominations connected to move with said shaft, and selectively settable means representing distance values for permitting and preventing rotation of said disks to control the travel and stopping of said shape relatively to the punching means.

38. A machine for punching structural shapes including in combination punching means, and means for successively progressing and stopping a shape in proper position to be punched, said means including a shaft rotatable proportionately to the travel of said shape, and a plurality of rotatable disks representing distance denominations connected to move with said shaft, and means for permitting and preventing rotation of said disks to control the travel and stopping of said shape relatively to the punching means, and means for restoring said disks.

39. A machine for punching structural shapes including in combination punching means, and means for successively progressing and stopping a shape in proper position to be punched, said means including a shaft rotatable proportionately to the travel of said shape, and a plurality of rotatable disks representing distance denominations connected to move with said shaft, and selectively settable means representing distance values for permitting and preventing rotation of said disks to control the travel and stopping of said shape relatively to the punching means, and means for restoring said disks preparatory to another setting.

40. A machine for punching structural shapes including in combination punching means, and means for successively progressing and stopping a shape in proper position to be punched, said means including a shaft rotatable proportionately to the travel of said shape, and a plurality of rotatable disks representing distance denominations connected to move with said shaft, and selectively settable means representing distance values for permitting and preventing rotation of said disks to control the travel and stopping of said shape relatively to the punching means.

punching means, and automatic means for restoring said disks preparatory to another setting.

41. A machine for punching structural shapes including in combination punching means, and means for successively progressing and stopping a shape in proper position to be punched, said means including a shaft rotatable proportionately to the travel of said shape, and a plurality of rotatable members representing distance denominations and means for permitting and preventing their rotation relatively to each other to control the travel and stopping of said shape relatively to said punching means.
42. A machine for punching structural shapes including in combination punching means, and means for successively progressing and stopping a shape in proper position to be punched, said means including a shaft rotatable proportionately to the travel of said shape, and a plurality of rotatable members representing distance denominations and selectively settable means for permitting and preventing their rotation relatively to each other to control the travel and stopping of said shape relatively to said punching means.
43. A machine for punching structural shapes including in combination punching means, and means for successively progressing and stopping a shape in proper position to be punched, said means including a shaft rotatable proportionately to the travel of said shape, and a plurality of rotatable members representing distance denominations and means for causing a relative travel of said rotatable members so as to permit a desired travel and positioning of the shape relatively to said punching means.
44. A machine for punching structural shapes including in combination punching means, and means for successively progressing and stopping a shape in proper position to be punched, said means including a shaft rotatable proportionately to the travel of said shape, and a plurality of rotatable members representing distance denominations and means mounted upon said rotatable members for permitting and preventing their rotation relatively to each other to control the travel and stopping of said shape relatively to said punching means.
45. A machine for punching structural shapes including in combination punching means, and means for successively progressing and stopping a shape in proper position to be punched, said means including a shaft rotatable proportionately to the travel of said shape, and a plurality of rotatable members representing distance denominations and selectively settable means mounted upon said rotatable members for permitting and preventing their rotation relatively to

each other to control the travel and stopping of said shape relatively to said punching means.

46. A machine for punching structural shapes including in combination punching means, and means for successively progressing and stopping a shape in proper position to be punched, said means including a shaft rotatable proportionately to the travel of said shape, and a plurality of rotatable members representing distance denominations and selectively settable means for permitting and preventing their rotation relatively to each other to control the travel and stopping of said shape relatively to said punching means, and means for restoring said rotatable members preparatory to a new setting.

47. A machine for punching structural shapes including in combination punching means, and means for successively progressing and stopping a shape in proper position to be punched, said means including a shaft rotatable proportionately to the travel of said shape, and a plurality of rotatable members representing distance denominations and means for causing a relative travel of said rotatable members so as to permit a desired travel and positioning of the shape relatively to said punching means.

48. A machine for punching structural shapes including in combination punching means, and means for successively progressing and stopping a shape in proper position to be punched, said means including a shaft rotatable proportionately to the travel of said shape, and a plurality of rotatable members representing distance denominations and means for selecting one or more rotatable members for rotation and determining the amount of relative rotation of each to control the travel and positioning of the shape relatively to the punching means.

49. A machine for punching structural shapes including in combination punching means, and means for successively progressing and stopping a shape in proper position to be punched and a plurality of rotatable members representing distance denominations and being movable relatively to each other, connections for causing said members to have a total movement proportionate to the travel of the shape, and devices for distributing the total movement of all said members between the various members, to control the travel and stopping of said shape relatively to said punching means.

50. A machine for punching structural shapes including in combination punching means, and means for successively progressing and stopping a shape in proper positions to be punched, said means including a plurality of rotatable members representing distance denominations and having

translational movement relatively to each other, connections for causing said members to have a total movement proportionate to the travel of the shape, and devices 5 for distributing the total movement of all said members between the various members, to control the travel and stopping of said shape relatively to said punching means.

51. A machine for punching structural shapes including in combination punching means, and means for successively progressing and stopping a shape in proper positions to be punched, said means including a plurality of rotatable members representing distance denominations and being movable relatively to each other, connections for causing said members to have a total movement proportionate to the travel of the shape and devices for causing said members to move together or relatively to each other to distribute the total movement between the various members to control the travel and stopping of said shape relatively to said punching means.

52. A machine for punching structural shapes including in combination punching means, and means for successively progressing and stopping a shape in proper positions to be punched, said means including a plurality of rotatable members representing distance denominations and being mov-

able relatively to each other, connections for causing said members to have a total movement proportional to the travel of the shape, and devices carried by said relatively movable members to cause them to travel together to control the travel and stopping of the shape relatively to said punching means.

53. A machine for punching structural shapes including in combination punching means, and means for successively progressing and stopping a shape in proper positions to be punched, said means including a plurality of rotatable members representing distance denominations and having movement with respect to each other, connections for causing said members to have a total movement proportional to the travel of the shape, and devices carried by said relatively movable members for engaging other of said relatively movable members to cause them to travel together to control the travel and stopping of the shape relatively to said punching means.

In testimony whereof, I have signed my name to this specification, in the presence of two subscribing witnesses.

LOUIS A. HAWTHORNE.

Witnesses:

JOHN D. MORGAN,

EDWARD O. WURTS.
